(57) **CLAIM**

The ornamental design for a fabric window covering, as shown and described.

DESCRIPTION

FIG. 1 is a front and top perspective view of a first embodiment of the fabric window covering shown in an open position;

FIG. 2 is a rear and bottom perspective view thereof;

FIG. 3 is a front view thereof;

FIG. 4 is a rear view thereof;

FIG. 5 is a left side view thereof; the right side view is a mirror image;

FIG. 6 is a top view thereof;

FIG. 7 is a bottom view thereof;

FIG. 8 is a front and top perspective view of the design of FIG. 1 shown in a closed position;

FIG. 9 is a rear and bottom perspective view thereof;

FIG. 10 is a front view thereof;

FIG. 11 is a rear view thereof;

FIG. 12 is a left side view thereof; the right side view is a mirror image;

FIG. 13 is a top view thereof;

FIG. 14 is a bottom view thereof;

FIG. 15 is an enlarged detail view thereof of an exemplary part taken from the bottom of the front fabric sheet of the fabric window covering as shown in FIG. 10.

FIG. 16 is a front and top perspective view of a second embodiment of the fabric window covering shown in an open position;

FIG. 17 is a rear and bottom perspective view thereof;

FIG. 18 is a front view thereof;

FIG. 19 is a rear view thereof;
FIG. 20 is a left side view thereof; the right side view is a mirror image;
FIG. 21 is a top view thereof;
FIG. 22 is a bottom view thereof;
FIG. 23 is a front and top perspective view of the design of FIG. 16 shown in a closed position;
FIG. 24 is a rear and bottom perspective view thereof;
FIG. 25 is a front view thereof;
FIG. 26 is a rear view thereof;
FIG. 27 is a left side view thereof; the right side view is a mirror image;

FIG. 28 is a top view thereof;
FIG. 29 is a bottom view thereof; and,
FIG. 30 is an enlarged detail view thereof of an exemplary part taken from the bottom of the front fabric sheet of the fabric window covering as shown in FIG. 25.
The dark background is provided for contrast only for ease in viewing the claimed design and forms no part thereof. The middle perpendicular fabric layers of the first embodiment have texture. The middle perpendicular fabric layers of the second embodiment have no texture.
